(57) **CLAIM**

The ornamental design for a connector housing, as shown and described.

DESCRIPTION

FIG. 1 is a top plan view thereof;

FIG. 2 is a front elevation thereof;

FIG. 3 is a bottom plan view thereof;

FIG. 4 is a right-side elevation thereof;

FIG. 5 is a rear elevation thereof;

FIG. 6 is a cross section taken along the line 6—6 in FIG. 2; and,

FIG. 7 is a perspective view.

A left-side elevation of the connector housing is symmetrical with the right-side elevation, and is therefore excluded from the drawings.
